Primary Examiner — Elizabeth J Oswecki(57) **CLAIM**

The ornamental design for a Christmas tree light, as shown and described.

DESCRIPTION

FIG. 1 is a perspective view of a Christmas tree light showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged portion view labeled, "FIG. 9," shown in FIG. 1; and,

FIG. 10 is an enlarged portion view labeled, "FIG. 10," shown in FIG. 1.

The dash-dash broken lines in the drawings depict portions of the Christmas tree light that form no part of the claimed design. The dot-dash broken lines represent the boundary of the enlarged portion and form no part of the claimed design.
